UNITED STATES PATENT OFFICE.

RANSOME T. LEWIS, OF ELMIRA, NEW YORK.

ADJUSTABLE SIGN.

Application filed November 15, 1922. Serial No. 601,018.

To all whom it may concern:

Be it known that I, RANSOME T. LEWIS, a citizen of the United States, and resident of Elmira, in the county of Chemung and State of New York, have invented certain new and useful Improvements in Adjustable Signs, of which the following is a specification.

The invention relates to adjustable signs, and especially signs or cards bearing different indicia and intended to be arranged in different positions to give information to tradesmen as to the character or quantity of commodities to be delivered.

More particularly stated, the invention in one particular form, as disclosed herein, consists in an improved card or sign bearing distinctive indicia, such as different numbers to indicate to an ice deliveryman the number of pounds of ice desired, and provided with improved means for supporting the sign in any one of several different positions to definitely indicate the desired number.

The characteristics and advantages of the invention are further sufficiently explained in connection with the following detail description of the accompanying drawings which show several representative embodiments of the invention. After considering these it will be evident that other variations may be made within the principles of the invention, and I contemplate the employment of any structures that are properly within the scope of the appended claims.

In the drawings:

Fig. 1 is a perspective view of the invention in one form, in one operative position.

Fig. 2 is a vertical section of the same.

Fig. 3 is a perspective view of another form of the invention.

Fig. 4 is a section showing a fastening device.

Fig. 5 is a perspective view of another modification.

Fig. 6 is a front elevation showing a modified form of sign and holder.

Fig. 7 is a vertical section of the same.

As shown in Fig. 1, a rectangular card 1 of paste-board of substantial thickness is provided at the corners with suitable different indicia 2, which are in the present case different numbers to indicate the number of pounds of ice desired, these numbers being arranged so that the number of any corner arranged uppermost is right side up,

and this number being the one most easily read, is readily distinguished as the number constituting the order for the day.

At a suitable point, which is usually at or near the center of the card, the card is provided with one or more narrow slots, and in Fig. 1 the slot arrangement consists of a slotted cross 3 with the branches arranged at right angles and with the center of the cross in the present instance at the center of the card. Each of the four radial slots so produced points toward one of the numbers.

The slots are designed to cooperate with a holding member such as a hook 4 which may be a screw-hook or a "drive" hook with a straight, pointed shank, screwed or driven into any suitable support, such as a window frame, a porch upright or other available exterior part of a house. For instance, the shank may be inserted in a wooden upright 5, Fig. 1, or otherwise it may be inserted in a wooden base 6, and the base may in turn be permanently or removably placed on some exterior part of a building. The hook is most desirably one in which the hook portion proper 7 is a straight piece bent at a right angle to the shank 8, and this hook is screwed or driven into the base or support far enough so that the clearance between the hook portion 7 and the face 6 of the support is only slightly greater than the thickness of the card 1.

The card is then put in position by passing a straight portion of the cross slot 3 over the hook portion 7, turning the card until the desired number is uppermost and then permitting the card to drop, whereupon the card will hang in the determined position with the hook shank 8 engaging the upper end of the radial slot portion directed toward the predetermined number. The sign is effectively retained in the determined position by the force of gravity, and is also securely held against displacement by breezes, by the close engagement of the hook shank 7 with the face of the card. This hook engagement prevents any considerable outward displacement of any part of the card and securely retains it in the proper position.

The card may at any time be easily removed in an obvious way or may be readjusted to give a different indication by rotating it, whereupon another branch of the cross slot 3 will be engaged with the hook

shank and the card will drop into the new position and will be retained in that position in the manner previously described.

A variation shown in Fig. 3 consists of a 5 card or base 10 which may be card board or pulp board much thicker than the card of the previous example. These bases or base cards may be furnished independently of the cards or signs, which are frequently furnished by particular ice companies or other dealers, such as the card 11 bearing distinctive dealer's indicia 12. The base card is provided at the corners with distinctive indicia, such as different numbers, as in the 10 previous case, and in use the particular dealer's card 11 is secured to the base card 10 in any suitable way, for example by fastenings 13, which may be ordinary paper fasteners inserted through small apertures in 15 the two cards. For the ready insertion of the fasteners the base card may have holes previously provided, as at 14, Fig. 4, and the points of the fasteners may be easily pushed through the thinner material of the 20 card 11 and through the holes 14 and secured by bending in an obvious way, as indicated in Fig. 4.

The base card 10 or the outer card 11, or both of them, may be provided with cross 30 slots 3^a, substantially like the slot arrangement 3 of the previous example. When the slot arrangement is provided in only one of the cards, it is only necessary to provide another aperture of any sort in the other 35 card to permit the cross slot in the slotted card to cooperate with the hook.

The device as shown in Fig. 3 is operated as in the previous example, the hook in this case not being inserted into the base or support quite so far, or in other words, the 40 hook is screwed or driven into the upright or base 6 a proper distance to give only a slight clearance between the hook shank 7 and the outer face of the combined cards or 45 sign.

Fig. 5 shows another modification in which the sign or card 20 is triangular and is provided with indicia 2^a near the apexes of the triangle. To correspond with this indicia arrangement the card slot 21 is in triangular form. The operation of this form of the device is readily understood from previous explanations.

Figs. 6 and 7 show another modification in 55 which a nail or large tack 35 is inserted in the upright 5, to serve as a holder for the card instead of the hook previously described. Preferably this holder 35 is a nail having a head 36 of rather large diameter. To cooperate with this kind of holding device the card is provided with a substantially circular aperture 31 sufficiently large to pass over the nail head. This aperture is arranged to cooperate with slots 3 which may 60 be of any of the arrangements previously 65

described, or other suitable arrangements. For instance, the slots 3 are in the present case in cross form, as described in connection with Fig. 1, and the aperture 31 is arranged at the intersection of the slots. The 70 holder 35 is driven into the support so that the head is spaced away from the support 5 just far enough to provide moderate clearance for the thickness of the card 30. The card is put in position by passing the aperture 31 over the nail head and then the card is rotated to the proper position and permitted to drop, whereupon the nail shank 37 enters the appropriate slot 3 and the card hangs on the shank in the desired position 80 and is prevented from displacement by the large nail head 36.

It will be understood from these examples that the holding device for the card may be a suitable hook, nail or similar device. In 85 any case it has a shank adapted to be inserted in an upright support and an outer portion of considerable length at least in one direction and arranged at an angle to the shank, this outer angular portion being 90 represented in the case of the hook by the outer hook member 7, and in the case of a nail, Fig. 6, by the nail head 36, which has substantial length in a vertical direction 95 above the shank and also in this particular case has a considerable area about the shank tending effectively to prevent outward displacement of the sign.

It is evident from the foregoing specific examples that other variations may be made. 100

While cards are in many cases desirably made of paste-board, they may be of any suitable sheet material; for instance, in some cases they may be of sheet metal.

What I claim is:—

1. An indicating device comprising a card bearing different indicia and having an elongated slot, a holding member having a shank and an outer portion at a right angle to the shank, and an upright support, the holding member being inserted in the support to provide slight clearance for the card thickness, the shank passing through the card slot and the outer portion engaging the card face to prevent displacement. 105

2. An indicating device comprising a card bearing different indicia and having intersecting slots, a holder having an outer or head portion and a substantially straight right-angled shank, and an upright support, the holder being inserted in the support to provide slight clearance for the card thickness between the holder head and the support, the holder shank passing through one of the card slots whereby the card is held by gravity against rotation and the head portion engages the card face to prevent outward displacement. 115

3. An adjustable sign consisting of a piece of sheet material having distinctive indicia in 120

- spaced arrangement and provided with elongated slots adapted to cooperate with a holder and to support the sheet without rotation by gravitational effect, each slot being 5 directed toward one of the indicia.
4. An adjustable sign consisting of a card having distinctive indicia in spaced arrangement and provided with elongated intersecting slots adapted to cooperate with a holder- 10 shank, each slot being directed toward one of the indicia.
5. An indicating sign comprising a polygonal card having indicating indicia arranged near the polygonal angles and having 15 near its center intersecting narrow slots, a portion of each slot being directed toward one of the indicia, the slots being designed to co-operate with the shank of a headed holding member so that the sign may be easily 20 adjusted and held by gravity on said shank in any one of a plurality of indicating positions.
6. An indicating sign comprising a relatively thick base having different spaced 25 indicia, a card secured to one face of the base in substantially centered relation, the base and the card having substantially central cooperating holder-openings, the open- ing in one of the parts consisting of intersecting narrow slots, the slot branches being 30 directed toward the different indicia on the base, the slots being designed to co-operate with the shank of a headed holding member so that the sign may be easily adjusted and held by gravity on said shank in any one 35 of a plurality of indicating positions.
7. An indicating sign comprising a thick polygonal base having different spaced indicia near the polygonal angles, a card detachably secured to one face of the base in 40 substantially centered relation and bearing indicia, the base and the card having substantially central cooperating holder-openings, the opening in one of the parts consisting of intersecting relatively narrow slots, the 45 slot branches being directed toward the different indicia on the base, the slots being designed to co-operate with the shank of a headed holding member so that the sign may be easily adjusted and held by gravity on 50 said shank in any one of a plurality of indicating positions.

Signed at Elmira, in the county of Chemung and State of New York, this 2nd day of November A. D. 1922.

RANSOME T. LEWIS.
